UNITED STATES PATENT OFFICE.

EDWARD LEVY, OF MUNISING, MICHIGAN.

SNOWPLOW.

Application filed May 10, 1921. Serial No. 468,333.

To all whom it may concern:

Be it known that I, EDWARD LEVY, a citizen of the United States, and a resident of Munising, in the county of Alger and State 5 of Michigan, have invented a new and Improved Snowplow, of which the following is a description.

My invention relates to snow plows and particularly to a snow plow adapted to be 10 drawn or pushed by a tractor.

The general object of the invention is to provide a plow of the indicated character improved in various particulars whereby a track will be plowed ahead of sleighs with 15 which the apparatus is equipped, so that the machine will follow the plowed track. Provision is also made for steering the plow by hand to work independently of the tractive power that the plow may be kept in the center of the road regardless of the angle of travel. The snow plow is so arranged that a single operator can control the same with respect to raising or lowering a nose plow with which the plow is equipped as well as 20 25 with regard to controlling either the front or back sleigh for steering, as well as optionally raising or lowering mold boards provided at the sides of the apparatus in the rear of the nose plow.

Other important features and advantages 30 of the apparatus will clearly appear as the description proceeds.

Reference is to be had to the accompanying drawings forming a part of this specification, it being understood that the drawings are merely illustrative of one example 35 of the invention.

Figure 1 is a side elevation of a snow plow embodying my invention;

Figure 2 is a central longitudinal vertical 40 section;

Figure 3 is a plan view;

Figure 4 is a cross section on the line 4—4, 45 Figure 3;

Figure 5 is a cross section on the line 5—5, Figure 2;

Figure 6 is an enlarged longitudinal vertical section of the rear portion of the snow plow;

Figure 7 is a detail in horizontal section 50 through one of the side mold boards and its vertical guides;

Figure 8 is a side elevation of one of the sleighs;

Figure 9 is an enlarged cross section of one 55

of the runners and an anti-sluing device provided thereon.

In carrying out my invention in accordance with the illustrated example, a suitable main frame 10 is provided, having longitudinal side bars. Said frame is supported on a front sleigh 11 and a rear sleigh 12. A nose plow 13 is provided at the front of the apparatus and therefore forward of the front sleigh 11. On the apparatus at the 60 65 sides outside of the side main frame 10 are mold boards 14.

In the rear of the mold boards 14 are secured wings 15 swingable about vertical hinges 16 securing said wings at the front 70 portion of an auxiliary frame 17 rigid with the main frame. The wings 15 are adapted to be folded at the sides of the machine or to be swung outwardly in rearwardly flaring form. To hold the wings spread I provide swingable braces 18 secured at one end to the frame 17 by vertical hinges 19, the outer ends of said braces being adapted to engage against vertical cleats 20 on the wings 15 at the inner side or equivalent 75 80 members presenting shoulders for the outer ends of said braces. On each wing 15 at the outer side is a fixed snow elevator 21 advantageously V-shaped in cross section and in any event constituting a deflector presenting a front transversely curved surface, the elevator inclining rearwardly from the lower edge of the wing to a point at the top near the rear edge of the wing. Similar deflectors 22 are also provided on the wings at 85 the rear edges of the outside.

The front sleigh 11 turns about a vertical king bolt 23 passing through a cross bar 24 on the main frame and through a top cross bar 25 on the sleigh and joining the runners 90 thereof. Similarly, the rear sleigh 12 has a king bolt 23^a passing through a cross bar 24^a on the main frame and a cross bar 25^a on the sleigh 12. For steering the front sleigh by causing the same to turn about its king 100 bolt 23, I provide steering cables 26, or equivalent chains or the like secured at their outer ends to rearwardly extending arms 27 on the sleigh runners at the rear end or equivalent fittings for securing said cables. The cables 26 or equivalent flexible elements extend from the sides of the sleigh laterally outward in opposite directions and over sheaves 28, from which said cables run laterally inward to a drum 29 about which the cables re- 105 110

versely wind. The shaft 30 of the drum 29 turns in suitable bearings 31 and on said shaft is a worm wheel 32 meshing with which is a worm 33 on a vertical shaft 34 rising above the top of the frame 10 and provided with a handwheel 35 or other means for turning same. It will be seen that through the medium of the shaft 34 and worm drive, the drum 29 can be turned in either direction to wind in either cable 26 and pay out the other to turn the sleigh 11 about its bolt 23.

For steering the rear sleigh 12 a transverse cable or chain 36 is provided on said sleigh at the front and secured thereto is a forwardly extending arm 37 on a vertical shaft 38 extending in the main cross bar 38^a of the main frame 10, said shaft having at its upper end an arm 39 extending laterally outward and having connected therewith the rear end of a connecting rod 40 which extends forwardly along the adjacent side of the frame 10 to a connection with a hand lever 41 fulcrumed on the frame 10 at a point laterally outward from the handwheel 35. Thus, by throwing the lever 41 the shaft 38 will be turned to swing the arm 37 thereof to the right or left and exert a pull in one direction or the other on the cable or chain 36 to give the sleigh 12 a turning movement about its king bolt 23^a.

I provide on the runner of each sleigh 11 and 12 at the outside thereof, a longitudinal anti-slung plate 42 pivoted to the adjacent runner at its front end as at 43. The rear end of each plate is adjustably suspended by a vertical stud bolt 44 passing at its upper end through a bracket 45 on the runner and provided with set nuts 46 above and below said bracket. Similarly, the lower end 40 of the stud bolt 44 extends through a bracket 47 and is provided with upper and lower set nuts 48 above and below said bracket. On the said runner also at the outer side are guard keepers 49 offset at their outer ends 45 to overlap the plate 42. By adjusting the bolts 44 the lower ends of the plates 42 may be caused to extend below the sleigh runners to any desired extent to prevent sluing of the sleighs. Said plates in practice are 50 sharpened to cut into any ice in the roadway.

For raising or lowering the nose plow 13 it is secured to cross bars extending between longitudinal channel bars 50. Said bars 50 are secured at their rear ends by transverse pivot bolts 51 that they may rock vertically and at their forward ends they are rigidly fastened as at 52 to the plow 13 that the latter may swing vertically with the raising and lowering of the bars 50. The front end of the main frame 10 is curved, the curvature being struck with the pivots 51 as a center and the rear edge of the plow frame 13^a is similarly curved. At 60 65 the curved joint between the plow frame 13^a

and main frame 10 are secured offset plates 54. The illustrated raising and lowering means consists of a cable 55 secured at its forward end of the cross bar 50^a and running upwardly over a sheave 56 and then rearwardly along the frame 10 to a connection with a hand lever 57 secured to one of the side bars of the main frame, advantageously, at the opposite side of the frame from the lever 41, said levers being 75 in adjacent transverse planes to be conveniently operated from one point.

In order to raise or lower the side mold boards 14, I provide on the same a vertical plate 58 and bearing 59, said plate having a 80 brace 60. The plate 58 has vertical guided movement on a plate 61 on the frame 10. A vertical shaft 62 has threaded engagement with the bearing 59 and is provided at its upper end with a handwheel 63 or equivalent 85 operating means. The arrangement is such that the turning of the shaft 62 in one or other direction will raise or lower bearing 59 and impart vertical movement to the plate 58 thereby raising or lowering the 90 mold board 14.

For the hauling of the plow I provide draw rods 64, the rear ends of said bars being swingably secured as at 65 to a transverse draft bar 66 on the main frame 10. 95 The front ends of the cross bars 64 have eyes 67 or other means for hitching the same to a tractor. At the rear for pushing the apparatus by a tractor any suitable rear hitch (not shown) may be provided.

In the lowered position of the nose plow 13 the bars 50 may rest upon brackets 68 provided on the main frame at the front end. With the above-described arrangement, the nose plow which is of the V-type 105 will direct the snow laterally to the outer sides of the machine and the snow will be further deflected by the side mold boards 14, the wings finally further displacing the snow laterally, the upward inclination of 110 the rigid elevators contributing to the clearing of the road with the minimum power. It will be observed that the front sleigh 11 is positioned between the nose plow 13 and the side mold boards 14 while the rear plow 115 12 is positioned rearward of the side mold boards between the same and the swingable wings 15. The arrangement provides the maximum stability and an effective steering control.

A characteristic of the described snow plow is that the operator can control the same to keep on the outside of curves or the center of the road, a matter difficult if not impossible with the ordinary type of 125 plow.

I would state in conclusion that while the illustrated example constitutes a practical embodiment of my invention, I do not limit myself strictly to the mechanical details 130

herein illustrated, since manifestly the same can be considerably varied without departure from the spirit of the invention as defined in the appended claims.

5 Having thus described my invention, I claim:

1. In a snow plow, a frame, a nose plow on the frame at the front adapted to direct snow to both sides of the frame, flexible means to raise and lower said plow, mold boards on the frame at the outer sides rearward of the nose plow, means to vertically adjust the mold boards, a front sleigh supporting said frame in the rear of the nose plow, and a second sleigh supporting said frame rearward of the first sleigh.
2. In a snow plow of the class described, a frame, bars pivoted to the frame adjacent to the front end and extending beyond said front end, a nose plow rigid with said bars in front of the frame, means to swing said bars on their pivots for raising or lowering the plow, and a sleigh in the rear of the nose plow.
- 25 3. In a snow plow of the class described,

a frame, bars pivoted to the frame adjacent to the front end and extending beyond said front end, a nose plow rigid with said bars in front of the frame, a sleigh in the rear of said nose plow for supporting said frame, and flexible means to swing said bars on their pivots for raising or lowering the plow, said frame at the front and said plow at the rear presenting curves struck approximately from the pivotal center of said bars.

4. In a snow plow of the class described, a frame, bars pivoted to the frame adjacent to the front end and extending beyond said front end, a nose plow rigid with said bars in front of the frame, and flexible means to swing said bars on their pivots for raising or lowering the plow, said frame at the front and said plow at the rear presenting curves struck approximately from the pivotal center of said bars; together with curved plates on said curved portions at the outer sides of the joints.

EDWARD LEVY.
